UNITED STATES PATENT OFFICE.

IDA M. BARTLETT, OF CHICAGO, ILLINOIS.

DESIGN FOR A BICYCLE-PEDAL RUBBER MEMBER.

SPECIFICATION forming part of Design No. 30,915, dated May 30, 1898.

Application filed April 10, 1898. Serial No. 712,541. Term of patent 7 years.

To all whom it may concern:

Be it known that I, IDA M. BARTLETT, a citizen of the United States, residing at Chicago, in the county of Cook and State of Illinois, have invented and produced a new and original Design for a Bicycle-Pedal Rubber Member, of which the following is a specification, reference being had to the accompanying drawing, forming part thereof, in which the figure is a perspective view of a bicycle-pedal rubber member, showing my new design.

As shown in the drawing, the leading or material feature of my design consists of a

bar or piece A, having a longitudinal channel a, and at its middle a projection B, formed with a slot b or opening.

Having described my invention, what I claim as new, and desire to secure by Letters Patent, is—

The design for a bicycle-pedal rubber member, substantially as herein shown and described.

IDA M. BARTLETT.
